UNITED STATES PATENT OFFICE.

THOMAS J. GILBRIDE, OF SCRANTON, PENNSYLVANIA.

DESIGN FOR A HORSESHOE-CALK.

SPECIFICATION forming part of Design No. 28,853, dated June 14, 1898.

Application filed February 10, 1897. Serial No. 622,859. Term of patent 14 years.

To all whom it may concern:

Be it known that I, THOMAS J. GILBRIDE, of Scranton, in the county of Lackawanna, and in the State of Pennsylvania, have invented a certain new and original Design for Horseshoe-Calks; and I do hereby declare that the following is a full, clear, and exact description thereof, reference being had to the accompanying drawings, in which—

10 Figure 1 is a perspective view in an inverted position of a calk embodying my design, and Fig. 2 is a plan view thereof.

Letters of like name and kind refer to like parts in each of the figures.

15 The object of my invention is to provide a new and original shape or design for removable horseshoe-calks; and to this end said invention consists in the design for a horse-shoe-calk, substantially as hereinafter specified.

20 My design, as shown in the drawings, is embodied in a toe-calk, the body A of the calk having its outer face vertical and its inner face inclined upward and rearward in a straight line for a portion of the way toward the top and then curved concavely, as at a. On the upper side of the body, at its transverse center, is a projecting stud B. On each side of the body A, at the top thereof, there 25 is an extension or flange C, that projects ob-

liquely rearward from a corner of the body and has its extremity rounded on the arc of a circle and perforated with a hole or opening c. The sides of each flange or extension C are concavely rounded or curved, and the 35 rear face of the body A, at the top, is likewise curved, the curve thereof being a continuation of the contiguous side of the extension or projection C, so that thus the configuration from the extremity of one projection 40 to the other is a simple concave curve. It will be noted that the two projections extend from the body of the calk in diverging lines. The thickness of each projection gradually decreases toward its extremity from the point 45 of its connection with the body of the calk, and the curve a extends over a portion of the same.

Having thus described my invention, what I claim is—

50 The design for a horseshoe-calk, substantially as shown and described.

In testimony that I claim the foregoing I have hereunto set my hand this 2d day of February, 1897.

THOMAS J. GILBRIDE.
